A. L. Fuller.

Yarn Covering Mach.

N° 16,164.

Patented Dec. 2, 1856.

Inventor
A. L. Fuller

UNITED STATES PATENT OFFICE.

A. L. FULLER, OF CLINTON, MASSACHUSETTS.

COVERING THREAD WITH WOOL.

Specification of Letters Patent No. 16,164, dated December 2, 1856.

To all whom it may concern:

Be it known that I, ANDREW L. FULLER, of Clinton, in the county of Worcester and State of Massachusetts, have invented a new and useful Improved Sliver; and I do hereby declare that the following is a full, clear, and exact description of the same, reference being had to the drawings herewith presented and to the letters of reference marked 10 thereon.

The object of my invention is to enable me to make a sliver of the refuse waste, or short fiber stock, and to at the same time give it strength enough to be used in the 15 loom.

I am aware that slivers have been made of two materials both carded together, also by placing one between the other after leaving the card, and also by spinning the two together to form a thread of two substances 20 or different qualities of the same.

My invention differs from all these, and consists in placing a core in the interior or center of the sliver by introducing it into the 25 carded material as it is delivered by the comb, and by the combined action of the comb and condenser from the sliver around the core. To accomplish this, I attach to the frame of the card (see drawings in 30 which A represents the last roll, B the comb, C the condenser and D D the rolls) a stud or spindle F to hold a bobbin or ball of the

thread to make the core and pass the end of it (the thread) into the condenser C with the fiber as delivered by the comb B 35 the motion of which curles the fibers around the core and the rolls draw the whole through as condensed and perfect although the twist given is thrown out again and the core will be found in the center or nearly so. 40

Thus I am enabled to make a sliver capable of being used in the loom and drawn through by the shuttle somewhat after the manner of weaving hair, and make all kinds of quilted, wadded or padded goods for va- 45 rious purposes, though I do not claim the weaving of such goods, nor the use of wadding in the loom, neither do I claim making the sliver of two materials in order to spin a finer around a coarser, or vice versa, as I 50 am aware that is old. But

What I do claim as new and desire to secure by Letters Patent is:

I claim the above described mode of placing the core in the sliver and covering it 55 by the combined action of the comb B, and condenser C, so as to produce the sliver above described, and this I claim whether a twist be given to the sliver or not.

A. L. FULLER.
